UNITED STATES PATENT OFFICE.

EDWARD W. VINZ, OF MINNEAPOLIS, MINNESOTA.

STORM WINDOW.

Application filed February 15, 1926. Serial No. 88,266.

My invention relates to storm windows and an object in general is to improve the construction thereof. It is customary in cold climates to provide what are known as storm windows which are placed outside of the regular windows of the building. The storm windows commonly used consist of a frame which is suspended from the upper end so that when ventilation is desired, the storm window can be swung outwardly at the bottom and held in this open position by metal strips engaging the storm window and the main window frame. When thus opened, storm windows are apt to rattle and are frequently torn loose by high winds, and furthermore, entrance of burglars is made an easy matter. I am aware that it has been proposed to provide storm windows with a lower portion which can be slid upwardly for ventilation, but so far as I am aware, all such prior constructions have been made in such manner that easy entrance for burglars is afforded when the storm window is opened for ventilation. A particular object of my invention, therefore, is to provide a storm window which is so constructed and arranged that it can be opened sufficiently for ventilation without swinging the lower end outwardly and without providing an uncovered space through which burglars can enter the building.

The full objects and advantages of my invention will appear in connection with the detailed description thereof, and the novel features of my inventive idea will be particularly pointed out in the claims.

In the accompanying drawings which illustrate one form in which my invention may be embodied,—

Fig. 1 is an elevational view of the device as it appears from the inside of the building, and with the auxiliary window lowered. Fig. 2 is a similar view showing the auxiliary window raised. Fig. 3 is a similar view showing the auxiliary window entirely removed. Fig. 4 is an elevational view of the device as it appears from the outside. Fig. 5 is a view in section on the line 5—5 of Fig. 1. Fig. 6 is a view in section on the line 6—6 of Fig. 1. Fig. 7 is a view in section on the line 7—7 of Fig. 1. Fig. 8 is a view in section on the line 8—8 of Fig. 2. Figs. 5 to 8 are on a larger scale than Figs. 1 to 4.

Referring to the drawings, the numeral 10 designates the frame of a storm window which is adapted to be secured in suitable

manner in the main window frame outside of the customary sash. The frame 10 is provided with an intermediate cross bar 12 and a lower cross bar 14. A pane of glass 16 is secured between the cross bar 12 and the upper member of the frame while another pane of glass 18 is secured between the cross bars 12 and 14. By referring to Figs. 7 and 8, it will be noticed that the cross bar 12 is of the same thickness as the surrounding frame and that the cross bar 14 is of reduced thickness on the interior side of the window. Between the cross bar 12 and the bottom of the frame 10, the side members of the latter on their interior margins are partly cut away to form slideways 20 as best shown in Figs. 5 and 6 and these slideways are completed by securing metal angle strips 22 to the frame members by screws 24. An auxiliary frame 26 containing a pane of glass 28 is arranged to cooperate with the slideways and for this purpose, the side members of the auxiliary frame are rabbeted, as indicated at 30, in order to be engaged by the inwardly extending flanges of the angle strips 22. It is obvious that the auxiliary frame 26 may be inserted upon the slideways from the bottom of the main frame 10 and that it may be slid upwardly until the upper member thereof engages the cross bar 12 as shown in Figs. 2 and 8. It may be held in this upward position when ventilation is desired by means of hooks 32 thereon which are adapted to engage with eyes 34 carried by the surrounding frame. When the weather is too cold to permit of ventilation with comfort, the auxiliary frame 26 is slid downwardly into the position shown in Figs. 1 and 7 where it may be held by engaging the hooks 32 with eyes 36 carried by the main frame 10. In this latter position, the upper member of the auxiliary frame fits against the side of the cross bar 14 and the lower member fits against the side of the lower member of the main frame 10 which it will be noted is of reduced thickness to correspond with the thickness of the cross bar 14. When the frame 26 is thus secured, it is prevented from dropping entirely down so that a tight closure is insured in connection with the main frame, and at the same time the auxiliary frame is held up somewhat from the window sill so that there is no liability of its freezing fast thereto. As best shown in Fig. 4, a frame 38 containing a wire screen 40 is secured to the outside of the main frame 10.

between the bottom thereof and the position occupied by the cross bar 14 so as to cover the ventilating space.

The operation and advantages of my invention will now be obvious. The frame 10 may be secured in the window frame of the building in any suitable manner. It may be conveniently hung at the top in the manner customary with storm windows now in use, and when fastened at the bottom on the inside cannot be swung outwardly by anyone on the outside. The operation of the sliding frame 26 has already been referred to. When it is desirable to remove this auxiliary frame for cleaning the glass or when it is not desired to use the same in the summer time, the frame 10 may be released at the bottom and swung outwardly whereupon the auxiliary frame may be readily slid off the bottom, and then the frame 10 may be again fastened in position. When my device is used, it is impossible for burglars to readily enter through the window, since the open space left by the raising or entire removal of the auxiliary frame is ordinarily too small for this purpose, and the breaking of the glass would almost certainly arouse the occupants of the building. Furthermore, this space is protected by a wire screen secured in place, the cutting away or removal of which would attract attention.

I claim:

1. A storm window comprising a main frame, an intermediate cross bar for said frame of the same thickness as the side members of said frame, a pane of glass in the space above said cross bar, a lower cross bar substantially midway between said intermediate cross bar and the lower member of said frame, said lower cross bar being of reduced thickness and being flush with the outer surface of said side members, a pane of glass in the space between said intermediate cross bar and said lower cross bar, the space between said lower cross bar and the lower member of said frame

being open, slideways on the inward margins of said side members extending between said intermediate cross bar and the lower portion of the main frame, an auxiliary frame mounted in said slideways, and a pane of glass in said auxiliary frame, said auxiliary frame being disposed in a vertical plane entirely outside said lower cross bar whereby said auxiliary frame may be slid from lower position in which the glass therein closes said open space into upper position with the upper auxiliary frame member in engagement with said intermediate cross bar.

2. A storm window comprising a main frame, an intermediate cross bar for said frame of the same thickness as the side members of said frame, a pane of glass in the space above said cross bar, a lower cross bar substantially midway between said intermediate cross bar and the lower member of said frame, said lower cross bar and said lower frame member being of reduced thickness and being flush with the outer surface of said side members, a pane of glass in the space between said intermediate cross bar and said lower cross bar, the space between said lower cross bar and the lower member of the main frame being open, slideways on the inward margins of said side members extending between said intermediate cross bar and the lower portion of the main frame and lying in a vertical plane outside of the aforesaid lower frame member, an auxiliary frame mounted in said slideways, and a pane of glass in said auxiliary frame, said auxiliary frame being disposed in a vertical plane entirely outside said lower cross bar whereby said auxiliary frame may be slid from lower position in which the glass therein closes said open space into upper position with the upper auxiliary frame member in engagement with said intermediate cross bar.

In testimony whereof I hereunto affix my signature.

EDWARD W. VINZ.
